CLAIM

The ornamental design for a cervical plate, as shown and described.

DESCRIPTION

FIG. 1 is a top perspective view of a cervical plate showing my new design;

FIG. 2 is a top plan view thereof;

FIG. 3 is a bottom plan thereof;

FIG. 4 is a right side elevation thereof, the left side being a mirror image; and,

FIG. 5 is an end elevation thereof, the end opposite being a mirror image.

The broken lines shown in the drawings are included for the purpose of illustrating structure and form no part of the claimed design.
